LUCIA MANNESCHMIDT, OF NEW BRUNSWICK, NEW JERSEY.

TEST-PLUG.

1,284,404.

Specification of Letters Patent. Patented Nov. 12, 1918.

Application filed March 30, 1917. Serial No. 158,686.

To all whom it may concern:

Be it known that I, LUCIA MANNESCHMIDT, a citizen of United States of America, residing at New Brunswick, in the county of 5 Middlesex and State of New Jersey, have invented new and useful Improvements in Test-Plugs, of which the following is a specification.

This invention relates to test plugs, designed particularly for use by plumbers in 10 soil, waste and vent pipe connections, wherein through the use of this implement, the pipe can be effectually sealed for testing purposes.

15 In ordinary pipes, as heretofore proposed in practice, it has been customary to provide a pipe with an additional length beyond that necessary for final connection with the usual floor plate, and fixtures which additional 20 length permitted a sealing of the end of the pipe for the testing operation, and which additional length was subsequently cut off to reduce the pipe to a proper length for the setting of fixtures.

25 The primary object of the present invention is the provision of a single tool adapted to coöperate with pipes of normal length, which tool is constructed to provide a means whereby the terminal edge of said pipe may 30 be initially flared and sealed without necessitating the use of solder or the like. There is by this invention, a clear saving of solder and labor and the additional length of pipe is entirely unnecessary and hence its waste 35 is avoided.

A preferred type of the improved implement or tool is illustrated in the accompanying drawings in which:—

Figure 1, is a front elevation of the tool 40 applied to the pipe for sealing the same.

Fig. 2, is a diametrical cross sectional view through the same, showing in broken lines, the tool operated to the extent of destroying the seal, and prior to the separation of the 45 tool proper from the pipe end.

Fig. 3, is a detail cross sectional view on the line 3—3 of Fig. 2, and

Fig. 4, is a detail perspective view of one 50 of the clamping ring sections removed from the tool.

Fig. 5, is a detail perspective view of the nut.

Fig. 6 is a perspective view of a portion of the device showing a slightly modified form thereof.

Fig. 7 is a plan view of the ring sections employed in connection with the modification.

In detail structure, in the preferred embodiment illustrated, the tool is illustrated 60 as comprising a ring 1, having a yoke 2, rising from and extending over the ring, the center of the yoke being spaced an appreciable distance above the plane of the ring.

The yoke center above the ring is formed 65 with an opening 3, here shown as rectangular, and slidably mounted in this opening is an adjusting nut 4. The nut is mounted for longitudinal movement axially of the ring 1. An operating screw 5, is arranged for 70 threaded connection with the nut, having at its upper end, an operating handle 6, whereby the screw may be turned. A sealing plug 7, is secured to the lower end of the nut, the plug being preferably of hollow 75 construction having an unbroken bottom wall 8, and an upstanding side wall 9. The connection between the sealing plug and screw is comparatively free as by the ball and socket connection illustrated. The edge 80 wall 9, of the sealing plug is of particular formation in that its relatively lower portion 11, is of true cylindrical form and of a diameter slightly less than the normal diameter of the soil pipe. The edge wall above the 85 cylindrical portion 11, which will be hereafter termed, the guiding portion of the plug, is outwardly flared as at 12, the extent of flare or angular relation being that desired in the completed pipe end.

90 The plug is provided with diametrically opposed ears 13, to each of which through a connection as pins 19^a, there is loosely secured a section 15, of an external clamping ring. The sections 15, of the ring, when in ring 95 forming position, provide a member having an internal diameter corresponding to the external diameter of the pipe. Each section has an upper or edge flange 16, and a depending wall 17, the angular member formed 100

by the depending walls of the sections when in ring forming relation, presenting an external diameter corresponding approximately to the internal diameter of the ring 5 1. The depending walls of the sections 15, of the clamping ring, are cut away on upwardly inclined lines forming guiding edges 18, arranged in the withdrawing or inoperative movement of the plug parts to engage 10 the upper edge of the ring 1, and so deflect the clamping ring sections so that they will be made to ride downwardly beyond the ring 1.

An operative withdrawal of the tool from 15 the flared end of the pipe is permitted through the connection of the ring sections with the sealing plug. For this connection each ring section has an ear 19, the ears of the respective sections being connected with 20 the ears 13, of the plug by pins 19^a, of an appreciable length and headed at the respective ends beyond the ears. The pins pass through slots 20, in the respective ears which are of such radial length as to permit a comparative free play of the parts on the pins. 25

In the application of the tool, the same is passed endwise over the pipe section 21, which pipe section as before stated, is of that exact length necessary for its final co-operation with the usual floor plate. In the initial application of the tool, the parts are arranged with the guide section of the sealing plug in the upper open end of the pipe, said guide section having such a fit with the 30 pipe as to guide the plug in movement. The clamping ring sections rest within the main ring 1, and below the upper edge of the pipe. The upper end of the threaded element or screw is then given a blow with a 35 hammer to drive the sealing plug into the pipe. The upper or flaring section of the sealing plug thus forces the pipe to the extent necessary for testing or sealing. The endwise movement of the screw is permitted 40 through the sliding co-operation of the nut with the yoke. The sealing action of the tool is secured by threaded movement of the screw element which moves the ring 1, and plug relatively of each other or more exactly, moves the ring 1, upwardly of the 45 pipe. The movement is continued until the clamping sections bind against the lower end of the flared portion of the pipe so that an effective sealing action of the plug is 50 had in the end of the pipe, the pipe end being clamped between the plug and clamping rings. In the reverse or separating movements of the tool, the rotation of the screw element in a direction opposite to that for 55 effecting the sealing operation, tends first to lift the plug from sealing co-operation with the pipe until such plug is at the limit of upward movement restrained by the connection between the plug and clamping ring 60

sections as the latter are still in more or less 65 clamping co-operation with the pipe end, being held by the pins 19^a. The further unscrewing movement tends to force the main ring downwardly, this movement being continued until the clamping action of the 70 clamping ring sections is broken, whereupon, the whole device drops on the pipe with the sealing plug again under the end of the pipe. The sealing plug then becomes the relatively fixed element, and the further 75 unscrewing action moves the main ring outwardly, while holding the clamp ring sections against such outward movement. This action is continued until the main ring rides below the lower edges of the clamping 80 ring sections, whereupon there is a tendency incident to the connection between the clamping ring sections and the plug to swing said sections outwardly. This action is materially aided by means of said 85 pins, and in fact, largely gained through the cutaway or guide edge portions of the depending walls of the clamping ring sections. These guide edge portions bear upon the upper edge of the main ring and in the 90 further downward movement, serve to guide or deflect the clamping ring sections so that they are directed to a position beyond the main ring. The tool may now be withdrawn over the end of the pipe. 95

The guiding portion of the sealing plug is of considerable importance in connection with this detail of the invention in that by its co-operation within the surface of the wall of the pipe, it insures a correct guiding 100 movement of the plug vertically and horizontally both under the guiding action to flare the pipe and the subsequent sealing action, so that the sealing plug will absolutely center itself with respect to the pipe, 105 with the result of completely and effectually sealing the pipe, notwithstanding that the plug may initially operate in other than a true sealing position. Furthermore, the connections between the various parts of the 110 structure are permanent that is, there are no radial separable parts. Under these circumstances, the tool is in entirety and may be handled, when not in use, as conveniently as if it consisted of a single member, there 115 being no possibility of a separation of parts to interfere with its effective operation.

A slightly modified construction is shown in Figs. 6 and 7, in which, to provide a positive means for causing the clamping ring sections to swing outwardly in the release operation of the tool, the arms of the yoke 2, adjacent their connection with the clamping ring and on their inner surface, are formed with upwardly divergent slots or channels, 120 25, and the inner or meeting ends of the clamping ring sections provided with lugs 26, to slidably seat in said slots or channels. 125

As the clamping ring and yoke move downwardly, as described in the release operation, the clamping ring sections are forced to move outwardly, and thus sufficiently beyond the main ring to permit withdrawal of the tool from the pipe.

What is claimed is:

1. A test plug, comprising, a supporting member adapted to coöperate with a pipe end of uniform internal diameter, and a combined sealing and flaring member operatively connected with the sealing member for operating on the pipe beyond the supporting member.
- 15 2. A test plug, for pipes of uniform internal diameter comprising, a supporting member arranged to be mounted upon the pipe, and a combined sealing plug and flaring member adjustably mounted in the supporting member for operating on the pipe beyond the supporting member.
- 20 3. A test plug for pipes of uniform internal diameter comprising, a supporting member to engage the pipe, a combined sealing and flaring plug, and a threaded and limited sliding connection between the plug and supporting member, said plug engaging the pipe beyond the supporting member.
- 25 4. A test plug for pipes comprising, a supporting member adapted to loosely engage the pipe end, a sealing plug having an inclined section for pipe flaring action, a member held against other than a sliding movement in the supporting member, and an adjusting rod having threaded connection with the sealing member and connected to the sealing plug.
- 30 5. A test plug for pipes, comprising, a supporting member to loosely engage the pipe, a combined sealing and flaring plug having sliding and threaded connection with the supporting member, and clamp ring sections to externally engage the pipe section in the sealing coöperation of the plug therewith.
- 35 6. A test plug for pipes, comprising a supporting member to loosely engage the pipe, a combined sealing and flaring plug having sliding and threaded connection with the supporting member, clamp ring sections to externally engage the pipe section in the sealing coöperation of the plug therewith, the clamping rings being held in engagement with the pipe end by the supporting member.
- 40 7. A test plug for pipes, comprising, a supporting member to loosely engage the pipe, a combined sealing and flaring plug having sliding and threaded connection with the supporting member, clamp ring sections to externally engage the pipe section in the sealing coöperation of the plug therewith, the clamp ring sections being loosely connected to the sealing plug.
- 45 8. A test plug for pipes, comprising a supporting member to loosely engage the pipe, a combined sealing and flaring plug having sliding and threaded connection with the supporting member, clamp ring sections to externally engage the pipe section in the sealing coöperation of the plug therewith, the clamp ring sections being loosely connected to the sealing plug.
- 50 9. A test plug for pipes comprising, a main ring arranged to loosely encircle the pipe, a yoke carried thereby, a nut mounted in the yoke and held against other than sliding movement, an operating rod threaded in the nut, and a plug having free universal connection with the lower end of the rod, said plug having a peripheral surface formed to provide a guiding section and a pipe end flaring section.
- 55 10. A test plug for pipes comprising, a main ring arranged to loosely encircle the pipe, a yoke carried thereby, a nut mounted in the yoke and held against other than sliding movement, an operating rod threaded in the nut, and a plug having free universal connection with the lower end of the rod, said plug having a peripheral surface formed to provide a guiding section and a pipe end flaring section, and clamping ring sections adapted to engage the outer surface of the pipe beneath the flared portion thereof in the sealing coöperation of the plug with the pipe.
- 60 11. A test plug for pipes comprising, a main ring arranged to loosely encircle the pipe, a yoke carried thereby, a nut mounted in the yoke and held against other than sliding movement, an operating rod threaded in the nut, and a plug having free universal connection with the lower end of the rod, said plug having a peripheral surface formed to provide a guiding section and a pipe and flaring section, clamping ring sections adapted to engage the outer surface of the pipe beneath the flared portion thereof in the sealing coöperation of the plug with the pipe, said clamp ring section having pin and slot connections with the sealing plug to permit a comparatively free movement of the sections with respect to the plug.
- 65 12. A test plug for pipes, comprising a supporting member to loosely engage the pipe, a sealing plug operable in said member, clamp-ring sections to exteriorly engage the pipe section in the sealing coöperation of the plug therewith, and coöoperating guiding means on the ring sections and member.
- 70 13. A test plug for pipes, comprising, a supporting member to loosely engage the pipe, a sealing plug operable in said mem-

ber, clamp-ring sections to exteriorly engage the pipe section in the sealing coöperation of the plug therewith, said member being formed with inclined ways, and guide lugs carried by the ring sections to seat in said ways for guiding the sections.

14. A test plug for pipes, comprising a supporting member to loosely engage the pipe, a sealing plug operable in said mem-

ber, clamp-ring sections to exteriorly engage the pipe section in the sealing coöperation of the plug therewith, said member being formed with downwardly convergent intersecting ways, and lugs on the ring sections to engage said ways.

15

In testimony whereof I affix my signature.

LUCIA MANNESCHMIDT.
